MULTIPLE OPERATED FASTENING END
MEMBERSHoward J. Murphy, Greenwood, Mass., assignor
to United-Carr Fastener Corporation, Cam-
bridge, Mass., a corporation of Massachusetts

Application February 27, 1935, Serial No. 8,538

10 Claims. (Cl. 24—205)

My invention aims to provide improvements in multiple operated fastening devices and relates particularly to improvements in separable bottom stops and top stops.

5 Reference is hereby made to my divisional application Serial No. 172,003, filed October 30, 1937.

In the drawing which illustrates preferred embodiments of my invention:—

10 Figure 1 is a front elevational view of a multiple operated fastening strip showing my invention;

15 Fig. 2 is a rear elevational view of the invention illustrated in Figure 1, but with a portion of the slider broken away to illustrate the top stop;

Fig. 3 is a part sectional view of the lower end of the device showing the manner of engagement of the members of the separable bottom stop just prior to complete engagement;

20 Fig. 4 is a view of the parts shown in Fig. 3 as they appear during the beginning of engagement of the parts;

Fig. 5 is an enlarged section taken on the line 5—5 of Figure 1;

25 Fig. 6 is an enlarged section taken on the line 6—6 of Figure 1;

Fig. 7 is an enlarged section of the top stop taken on the line 7—7 of Figure 1;

Fig. 8 is a plan view of the blank from which 30 the female member of the separable bottom members is formed;

Fig. 9 is a view showing the next step in bending the blank shown in Fig. 8;

Fig. 10 is an edge view of the intermediate form 35 of the female member shown in Fig. 9;

Fig. 11 is an end view of the device shown in Figs. 9 and 10;

Fig. 12 is an enlarged section of the male member and loop of the female member taken on 40 the line 12—12 of Figure 1; and

Fig. 13 is an elevational view of the parts of the separable bottom members with the fastener element engaging means on the male member.

Referring first to the embodiment of my invention selected for illustration of the separable bottom stop members and the parts of a so-called multiple operated or slide fastening device associated therewith, I have shown (Figs. 1, 3, and 4) a female member 1 attached to one end of a stringer 2 in the form of a tape having a beaded edge 3 and a male member 4 attached to one edge of a stringer 5 having a beaded edge 6.

The female member is preferably formed from 45 sheet metal and in its initial state is in the form

of a blank like that illustrated in Fig. 8. This blank is folded in any suitable manner so that it takes the form illustrated in Figs. 9, 10, and 11 and then the lateral projections 7 and 8 are clamped together, as shown in Figs. 1 and 5. 5 Thereafter the stringer-engaging portions 9 of the female member are bent to the shape shown in Figs. 1 and 2. The reason for having the stringer-engaging portions 9 more curved in the first stages of the forming of the female member will be apparent from an inspection of Figs. 8 and 9 because their lower ends must be spaced substantial distances apart in order to provide sufficient material between them at the lower end of the blank (Fig. 8) to form the loop portion 10 10 which is adapted to cooperate with the male member 4 in a manner more fully hereinafter described. The female member is also provided with tooth-like projections 11 extending from opposed edges of the stringer-engaging portions 9 15 to assist in holding the female member in position on the stringer 2. Furthermore, the female member is provided with fastener element engaging means herein illustrated as two fastener-engaging members 12—12, as shown in Figs. 1, 8, 20 25 and 9.

The male member 4 is formed from sheet metal and is more or less in the form of a pin substantially U-shaped in cross-section (Fig. 6) and is clamped to the bead 6 on the stringer 5. 30

The inter-engaging parts of the separable end members comprise the loop portion 10 of the female member 1 and the slightly thinned portion 13 of the male member 4, as clearly shown in Figs. 1, 2, and 12. In order to clamp the female member securely to the bead 3 of the stringer 2, I have found that the ends of the loop 10, adjacent to where they join the stringer-engaging portion 9, should be clamped together. Thus the clamping projections 7 and 8 have been provided for that 40 purpose. Therefore it is necessary to have the loop 10 extend below the end of the stringer 2. It is also, therefore, necessary to have the loop-engaging portion 13 extend below the stringer 5. 45 A neat, durable, and simple attachment of the female member 1 and the male member 4 is provided by so forming each stringer that the bead portions will extend along one side edge and then along the lower edge of each stringer, as clearly shown in Figs. 1 and 2. This formation is carried 50 out by taking a stringer having a bead portion extending along one side edge and first cutting a slit in the stringer from the beadless edge to a point adjacent the beading at the other edge; the slit extending, in my preferred form, at sub- 55

stantially a right-angular direction to the beading. The distance from the slit to the free end of the stringer should be substantially equal to the width of the stringer. Another slit is then 5 cut from the beadless edge between the first slit and the free end to meet the first slit substantially adjacent to the beading, thereby cutting a triangular-shaped notch in the stringer, which divides the stringer into a main portion and an end portion. The bottom edge of the end portion is 10 now twisted at substantially 90 degrees so that it will lie along the beadless edge of the main portion. As a result, the beaded edge of the end portion will lie along the lower end of the stringer 15 providing, when in final position, a bead portion in the form of a continuous member extending along one side edge and then along the lower edge of each stringer, as clearly shown in Figs. 1 and 2. This position of the bead is maintained 20 by overlapping the portion 14 (Fig. 2) with relation to that portion of the stringer above it and then holding the overlapping portions together by cement or any other suitable means. The portion 15 of the stringer 5 is overlapped and secured with 25 respect to the stringer 5 in the same manner.

To the bead of each stringer 2 and 5 I have attached a series of fastening elements 16 which may be of any well known construction. I prefer, however, to use fastening elements each of which 30 has a projection 17 on one face and a recess 18 on the other face, as illustrated in Fig. 2. I have also provided a slider 19 which moves relative to the fastening elements 16 to engage and disengage them in the usual manner.

35 My improved end separable members secured to the stringers 2 and 5 just beyond the lower ends of the rows of fastening members 16, as heretofore described, are simple in construction, durable, easy to operate and particularly desirable when the stringers are attached to articles 40 having openings which are to be completely opened at both ends. Assuming that the stringers are entirely separated, engagement thereof by means of the fastening elements 16 is effected 45 by moving the slider to the lowest position on the stringer 2 where it passes over all but the loop portion 10 of the female end separable member 1, as clearly shown in Fig. 4. Then the operator grasps the lower end of the stringer 5 and inserts 50 the male member 4 into the slider (Fig. 4) and moves it downwardly through the slider (with the stringer passing out through the groove between the usual upper and lower portions of the slider not herein shown in detail) until the loop-entering portion 13 enters the loop 10, as shown in 55 Fig. 3. It will be noted that the edges of the female member 1 and the male member 4 adjacent to the outer edges of the stringers 2 and 5 are so shaped that they will not interfere with 60 each other during the engaging operation and to this end these edges are so shaped that they diverge slightly from each other from top to bottom of the members, as clearly shown in Figs. 1 and 2. Thus there is a sort of rocking action 65 which takes place between the male member 4 and the female member 1 during engagement of those members, the final rocking operation taking place when the slider is pulled upwardly after the male member has reached the position shown 70 in Fig. 2. Thus as the parts pass through the slider their lower ends move outwardly to positions shown in Figs. 1 and 2. It will be apparent to anyone skilled in the art that the elongated loop 10 is therefore a necessary feature to permit 75 proper engagement of the parts.

As the slider is moved upwardly from a position shown in Fig. 3, the first two fastening elements 16-16 on the stringer 5 are brought into engagement with the fastener-engaging members 12-12 provided as integral parts of the female member 1 at the upper end thereof, thus cooperating to hold the end members together and prevent accidental separation of the end fastening members adjacent to their upper ends. It is, of course, understood that the loop 10 and loop-engaging portion 13 cooperate to prevent accidental separation of the end separable fasteners at their lower end. Furthermore, it is clear that the slider can be moved upwardly only when the end members are engaged as shown in Fig. 3. 15

One trouble encountered with fastening means of the type illustrated and described has been in connection with the fastening members 16 becoming accidentally disengaged below the slider thereby preventing downward movement of the 20 slider beyond the point where the fasteners are disengaged. In order to make it easy to place the parts in proper operating positions after such an accident I have provided a simple and efficient stop member 20, herein illustrated as being secured to the stringer 2 just beyond the upper end of the series of fastening elements 16 secured to that stringer. This stop member is provided with opposed stringer-engaging portions 21-21 secured to opposite sides of the stringer 2 as by 30 rivets 22 and are connected adjacent to the bead 6 by a relatively narrow beaded portion 23 for purposes hereinafter described. This stop member 20 has a pair of oppositely projecting ears 24-24 which prevent the slider from being moved 35 entirely past the stop member. Opposite this stop member 20 on the other stringer 5 there is provided fastening elements 16 which are to act as means to prevent that stringer from pulling through the slider when in its uppermost position. I have attached to the stringer 5 beyond the series of fastening elements 16 a clamping piece 26 which acts mostly as a protector against 40 displacement of the last fastening element 16 on that stringer. 45

When the slider is moved to a position where it engages the ears 24-24 of the stop member 20 (Fig. 2) the stringers may be separated after becoming accidentally disengaged by merely grasping them and pulling them apart laterally 50 to unfasten the fastener member 16. As the last two fastener members are disengaged just below the slider, then the remaining fastening members (herein shown as two in number) on the stringer 5 may be moved out of the bottom of the slider 55 because the width of the bead 23 of the stop member 20 is sufficiently narrow to permit passage of the fastening element 16 and the clamping piece 26 between the outer edge of the bead and the wall of the slider, as clearly illustrated in 60 Fig. 2. After the stringer 5 has been pulled entirely free from the slider 19 then the slider may be moved to the bottom of the stringer 2 and the end separable fastening element may be engaged and the slider moved upwardly again properly to engage the fastening members 16.

Referring now to Fig. 13, I have shown end fastening members of the same construction and operation as those described in connection with Figs. 1, 3, and 4, except that the fastener-engaging members 12-12 are on the male member instead of the female member. This is to show that the members may be made either way to secure the desired results.

While I have illustrated and described preferred 75

embodiments of my invention, I do not wish to be limited thereby, as the scope of my invention is best defined by the following claims.

I claim:

1. In a multiple operated fastening device having two stringers each having a series of fastening elements attached to an edge and adapted to be engaged and disengaged, a slider for engaging and disengaging the fastener elements, and end fastening means engageable and disengageable to permit complete separation of the stringers, said end fastening means comprising a male member attached to the edge of one stringer adjacent to one end of a series of fasteners, a female member attached to the other stringer adjacent to one end of the other series of fastener elements and having means receiving at least a portion of said male member to hold the end members against lateral separation and one of said end members having an integral fastening means projecting laterally beyond an edge thereof adjacent to the edge of the stringer to which it is attached, said fastening means engaging with at least one of the fastening elements of the series of fastening members on the other stringer from the one to which that end member is attached thereby to assist in preventing accidental separation of the end fastening members.

2. In a multiple operated fastening device having two stringers each having a series of fastening elements attached to an edge and adapted to be engaged and disengaged, a slider for engaging and disengaging the fastener elements, and end fastening means engageable and disengageable to permit complete separation of the stringers, said end fastening means comprising a male member attached to the edge of one stringer adjacent to one end of a series of fasteners, a female member attached to the other stringer adjacent to one end of the other series of fastener elements and having means receiving at least a portion of said male member to hold the end members against lateral separation and one of said end members having a pair of integral fastener members engaging a fastener element of the other series between them to assist in holding the end fastening members against accidental separation.

3. In a multiple operated fastening device having two stringers each having a series of fastening elements attached to an edge and adapted to be engaged and disengaged, a slider for engaging and disengaging the fastener elements, and end fastening means engageable and disengageable to permit complete separation of the stringers, said end fastening means comprising a male member attached to the edge of one stringer adjacent to one end of a series of fasteners, a female member attached to the other stringer adjacent to one end of the other series of fastener elements and having a loop at that end farthest from the series of fastening elements receiving a portion of the male member and said female member having integral fastener element engaging means at the other end projecting laterally beyond the edge of said member, said means cooperatively engaging fastening elements on the stringer above said male member to assist with said loop in holding the end fastening members against accidental separation.

4. In a multiple operated fastening device having two stringers each having a series of fastening elements attached to an edge and adapted to be engaged and disengaged, a slider for engaging and disengaging the fastener elements, and end fastening means engageable and disengageable to permit complete separation of the stringers, said end fastening means comprising a male member

fastening means engageable and disengageable to permit complete separation of the stringers, said end fastening means comprising a male member attached to the edge of one stringer adjacent to one end of a series of fasteners, said male member being in the form of a pin substantially U-shaped in cross-section and being slightly thinned at its lower end, a female member attached to the other stringer adjacent to one end of the other series of fastener elements and having a loop at that end farthest from the series of fastening elements receiving a portion of the male member and the loop of said female part and the thinned portion of said male member extending beyond the lower edges of their respective stringers thereby to permit clamping together of the ends of said loop for the purpose described.

5. The female member of a separable end fastening of the class described comprising a one-piece sheet metal part having opposed stringer-engaging portions, a loop extending laterally from said stringer-engaging portions, said loop having projecting end portions adjacent to where the material of said loop joins said stringer-engaging portions and clamping means securing said loop ends together adjacent to where they join the stringer-engaging portions.

6. The female member of a separable end fastening of the class described comprising a one-piece sheet metal part having opposed stringer-engaging portions, a loop extending laterally from said stringer-engaging portions at one end thereof, said loop having projecting end portions adjacent to where the material of said loop joins said stringer-engaging portions, said end portions extending from said stringer-engaging portions in the opposite direction from said loop and being inter-engaged to clamp the stringer-engaging portions together adjacent to said loop.

7. The female member of a separable end fastening of the class described comprising a one-piece sheet metal part having opposed stringer-engaging portions, a loop extending laterally from said stringer-engaging portions, said loop having projecting end portions adjacent to where the material of said loop joins said stringer-engaging portions and clamping means securing said loop ends together adjacent to where they join the stringer-engaging portions and stringer-engaging tooth-like projections extending from said stringer-engaging portions.

8. The female member of a separable end fastening of the class described comprising a one-piece sheet metal part having opposed stringer-engaging portions, a loop extending laterally from said stringer-engaging portions at one end thereof, said loop having projecting end portions adjacent to where the material of said loop joins said stringer-engaging portions, said end portions extending from said stringer-engaging portions in the opposite direction from said loop and being interengaged to clamp the stringer-engaging portions together adjacent to said loop and fastener-engaging projections adjacent to one end of said stringer-engaging portions for fastening engagement with fasteners on another stringer.

9. In a multiple operated fastening device having two stringers each having a series of fastening elements attached to an edge and adapted to be engaged and disengaged, a slider for engaging and disengaging the fastener elements, and end fastening means engageable and disengageable to permit complete separation of the stringers, said end fastening means comprising a male member

- attached to the edge of one stringer adjacent to one end of a series of fasteners, a female member attached to the other stringer adjacent to one end of the other series of fastener elements, each 5 stringer having a beaded edge and the extreme ends of said stringers adjacent to said end fastening members overlapping the remainder of said stringers so as to provide beaded edges at the lower ends of said stringers.
- 10 10. In a multiple operated fastening device having two stringers each having a series of fastening elements attached to an edge and adapted to be engaged and disengaged, a slider for engaging and disengaging the fastener elements, and

end fastening means engageable and disengageable to permit complete separation of the stringers, said end fastening means comprising a male member attached to the edge of one stringer adjacent to one end of a series of fasteners, a female 5 member attached to the other stringer adjacent to one end of the other series of fastener elements, each stringer having a beaded edge and the extreme ends of said stringers adjacent to said end fastening overlapping the remainder of said 10 stringers so as to provide beaded edges at the lower ends of said stringers.

HOWARD J. MURPHY.
